UNITED STATES PATENT OFFICE.

FRANK L. LINDEN, OF CHICAGO, ILLINOIS, ASSIGNOR TO THE LINDEN COMPANY, OF CHICAGO, ILLINOIS, A CORPORATION OF ILLINOIS.

DESIGN FOR A LIGHTING FIXTURE.

Application filed June 22, 1925. Serial No. 13,842. Term of patent 3½ years.

To all whom it may concern:

Be it known that I, FRANK L. LINDEN, a citizen of the United States, residing at Chicago, in the county of Cook and State of Illinois, have invented a new, original, and ornamental Design for Lighting Fixtures (Case 1), of which the following is a specification, reference being had to the accompanying drawings, forming a part thereof.

The figure is a front elevational view, showing my new design.

I claim:—

The ornamental design for a lighting fixture, as shown.

In witness whereof, I hereunto subscribe my name this 10th day of July, 1925.

FRANK L. LINDEN.
